FREDERICK STANLEY WALTON AND JOHN MCKENZIE, OF SMITHERS, BRITISH COLUMBIA, CANADA.

CATTLE GUARD.

Application filed April 30, 1926. Serial No. 105,841.

Our invention relates to improvements in cattle guards, and the object of the invention is to devise a simple construction of guard which may be easily installed, which is, readily adapted to be applied to tracks of any width or any number of tracks, which will be cheap, which will be safe, making it practically impossible for any animal to be caught fast in it, which will not form any serious obstruction to a train should any part of it inadvertently be left in a raised position, and it consists essentially of the arrangement and construction of parts as hereinafter more particularly explained.

Fig. 1 is a sectional view extending longitudinally through a track and showing our cattle guard in position, one member in the normal position and another member in the raised position.

Fig. 2 is a transverse sectional view through the track showing our cattle guard in the open position.

Fig. 3 is a fragmentary detail of the centre portion of one of the slat members forming our cattle guard.

Fig. 4 is a sectional view through Figure 3.

Fig. 5 is a detail view of the securing staple.

Fig. 6 is an enlarged sectional detail showing the means of mounting one of the slats on a supporting tie.

In the drawing like characters of reference indicate corresponding parts in each figure.

1 and 2 indicate the track rails and 3 the ballast. 4 are the ties, 4^x being a tie in close proximity to the crossing and 4° the tie next remote from the crossing. A supplemental tie 4¹ is placed beneath the usual tie 4^x. The tie 4° is bevelled off as indicated at 4². Between the ties 4^x and 4° an excavation is formed as indicated at 5, the bottom of the excavation sloping downward on a

line with the bevelled portion 4² of the tie 4°. 6 are a series of slats pivotally mounted on the tie 4° so that one portion thereof extends over the excavation 5 and the other portion extends outward from the excava-

tion so as to normally rest upon the track ties. Each slat is provided in its centre with a pair of orifices 7, the end walls of which converge downwardly and inwardly as indicated at 8 and 9. 10 is a reinforcing metal plate having orifices therein corresponding to the orifices 7 and having its end edges turned downward against the side edges of the slat so as to be secured by means of nails 12 or by any other suitable means.

13 is a staple, the spike members of which extend down through the orifices 7 so as to be driven into the tie 4° adjacent to the bevelled portion 4². The staple 13 is spiked down only a sufficient distance to secure the slat in place without interfering with its freedom of movement in a vertical plane.

The slats 6 extend longitudinally of the track parallel one with the other so as to extend between the track rails and the fence at each side of the trackway.

By this means should an animal attempt to pass down the track it will step upon one of the slats 6 extending over the excavation 5 thereby depressing that end of the slat and tilting the opposite end up in an inclined direction forming an effectual obstruction to its passage down the track.

As soon as the animal's foot is removed from the slat it will fall back to its normal position, the slat being so balanced as to be heavier at its outer end, which when relieved of the weight of the animal's foot will fall to the horizontal position thereby again leaving the track open. Should any slat for any reason stick in the upwardly inclined position very little harm will accrue therefrom as the train passing over the trackway will merely break off that particular slat.

From this description it will be seen that we have devised a very simple, cheap, easily installed cattle guard which is not liable to get out of order, and which is readily adaptable to a track of any width.

What we claim as our invention is:

1. In a cattle guard, the combination with the rails of a trackway and the ties extending thereunder with an excavation formed between two of such ties, of a plurality of

parallel slats each having a pair of orifices in the centre portion thereof, and a staple bridging that portion of the slat between the orifices thereof, and a vertical portion of the 5 staple extending part way through each orifice into the underlying tie.

2. In a cattle guard, the combination with the rails of a trackway and the ties extending thereunder with an excavation formed 10 between two of such ties, of a plurality of

parallel slats each having a pair of orifices in the centre portion thereof, a reinforcing plate provided with corresponding orifices, and a staple bridging that portion of the slat and plate between the orifices, and a 15 vertical portion of the staple extending part way through each orifice of the slat and plate and into the underlying tie.
